(57) **CLAIM**

The ornamental design for a snap-together stand, as shown and described.

DESCRIPTION

FIG. 1 is a front perspective view of a snap-together stand; FIG. 2 is a front elevation view thereof; the rear elevation view being an identical image thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is an exploded perspective view thereof.

The broken lines shown in the drawings illustrate portions of the snap-together stand that form no part of the claimed design.
